UNITED STATES PATENT OFFICE.

HARRY HALES ASBRIDGE, OF ASHTON-ON-MERSEY, ENGLAND.

CAM-GRINDING MACHINE.

Application filed July 27, 1925, Serial No. 46,412, and in Great Britain August 18, 1924.

This invention relates to machines for the grinding of the cams upon the cam shafts of internal combustion and like engines.

The object of my present invention is to provide means for the more expeditious and economical grinding of the said cams which are integral with the cam shafts and which have heretofore usually been ground one at a time.

10 My invention comprises the combination with means supporting the cam shaft, of a plurality of independently mounted rotating grinding wheels, each operating upon one cam, the positions and the feed movements of said wheels being controlled by master cams or formers, means for adjusting the position of the grinding wheels axially with relation to the cams, and means for reciprocating the cam shaft during 20 grinding.

My invention further comprises a grinding machine having in combination with a fixed head, sliding heads mounted upon a reciprocating table and carrying and rotating the cam shaft, the cams of which are to be ground, and a plurality of grinding wheels each carried by an arm or its equivalent capable of oscillatory movement under the action of a master cam or former, each 26 of said arms being pivotally mounted upon an adjustable slide.

My invention further comprises the details of construction hereinafter described.

Referring to the accompanying explanatory drawings:—

Figure 1 is a plan view of a machine constructed in one convenient form in accordance with my invention for grinding four cams simultaneously.

40 Figure 2 is an end elevation of the machine.

Figure 3 is a front elevation.

Figure 4 is a detail view of the fixed and sliding heads to be hereinafter referred to.

45 Figure 5 is an end elevation of the sliding head showing its attachment to the machine bed, and Figure 6 an end view of the fixed head.

The same reference letters in the different 50 views indicate the same parts.

The bed *a* of the machine carries on suitable slideways, four similar slides *b*, two at each side of the bed. Each slide has a spindle *c* therethrough having a hand wheel *d* at one end and a rack pinion *e* at the other

end to engage a rack *f* fixed in the machine bed. The said hand wheel *d* therefore serves for the setting of the slide in any desired longitudinal position on the bed.

Each of the slides *b* forms the support for 60 a fulcrum pin *g* about which can oscillate or turn an arm *h*. Upon the upper end of the latter is mounted a grinding wheel head *i* which is transversely adjustable by means of the hand wheel *j*. The lower end of each 65 oscillating arm *h* carries a slide *k* having a roller *m* thereon, the slide being adjustable in the arm.

At the lower part of the bed is mounted a shaft *n* adapted to carry the master cams 70 or formers *o*, upon which the rollers *m* bear. The number of master cams corresponds with the number of cams to be ground, the disposition of the master cams on the master cam shaft being identical with the position 75 of the cams on the cam shaft being operated upon. Further, the grinding wheels *p* and the rollers *m* swing in the same vertical plane and in their operative positions, the grinding wheel axes are practically verti- 80 cally above the axes of the fulcrum pins *g*.

The master cam shaft *n* is supported at its outer end by a longitudinally adjustable bracket *q*.

Each roller *m* is maintained in contact 85 with its master cam or former *o* by reason of the weight of the arm *h* so that the contour of the master cam imparts the necessary oscillatory movement to the arm *h* and the grinding wheel or milling cutter thereon to 90 produce the required contour on the cam on the camshaft.

The machine bed has thereon a fixed head *r* (see Figures 4 and 6) through which passes a spindle carrying at one end the face plate *s* and at the other end a worm wheel *t*. A table *u* is also mounted upon the bed *a* and is adapted to have a reciprocating movement imparted thereto as hereinafter described. Upon the table *u* are secured a headstock *v* and a tailstock *w*. The camshaft 2 to be machined is carried between the headstock *v* and tailstock *w* and rotated by the driving plate *x* on the former. The face plate *s* on the fixed head *r* rotates the driving plate *x* by means of the pins *y*, which pass through holes in the plate *z* on the spindle carrying the driving plate *x*. The arrangement of the driving pins *y* ensures the positive rotation of the disc *z* and driving plate 110 *x*.

x by the face plate *s* during the reciprocation of the table *u* carrying the heads *v* and *w*, which I call the sliding heads.

The master cam shaft *n* and the cam shaft

- 5 2 are rotated in unison by means of worm gearing from a common vertical shaft 3. Said shaft is rotated from the 3 speed belt pulley 4 through bevel wheels 6, 7 (Figure 3). The wheel 7 is upon a sleeve around the
- 10 shaft 3 which can be clutched to the said shaft by means of the clutch 8. At its lower end the shaft 3 carries a worm 9 which meshes with the worm wheel 10 on the master cam shaft *n*, and at its upper end carries
- 15 a worm 11 which meshes with the worm wheel *t* before referred to on the fixed head *r*. The belt pulley shaft also rotates through spur gearing 12, 12, a worm shaft 13, which drives a worm wheel 14 having a
- 20 crank pin 15 thereon. The latter oscillates a connecting rod 16 coupled to an arm 17 pivoted at 18 to the machine bed. A link 19 connects the table *u* to the arm 17 and so causes the reciprocation of the table during
- 25 the working of the machine to ensure even wear of the grinding wheels in the known manner. The point of connection between the link 19 and the arm 17 can be varied to adjust the length of stroke of the table *u*.
- 30 It will be seen that the disconnection of the clutch 8 does not interfere with the reciprocation of the table *u*.

Each oscillating arm *h* has thereon a screw threaded stop 20 (see Fig. 2) which can be

- 35 utilized to withdraw the rollers *m* from the master cams or formers whilst the saddles *b* are being adjusted along the machine bed.

It will be seen that the grinding wheel

heads are made right and left handed so that the grinding wheels can be brought close to each other in pairs. Each wheel or cutter is rotated by its own belt pulley 21.

In the construction illustrated, after four of the cams on the cam shaft 2 have been ground or machined, the saddles *b* are adjusted in position and the remaining four cams dealt with.

I claim:—

In a cam grinding machine, in combination, a bed, horizontally traversible slides 50 located at the opposite sides of said bed, with means for traversing said slides, arms each journalled about a pivot on a slide, grinding wheels heads each carried by an arm, and means for traversing said heads 55 upon said arms, a master cam carrying shaft located in the base of the machine, rollers upon said arms bearing upon the master cams, a table longitudinally traversible upon said bed, means upon said table for rotatably 60 supporting the cam shaft, the cams of which are to be ground, grinding wheels upon the grinding heads in vertical alignment with the rollers aforesaid, means imparting longitudinal reciprocating movement to said table, 65 a fixed head upon the machine bed, a drive shaft journalled in said head, means connecting said shaft with the cam-shaft-supporting-means for rotating the cam shaft and means for rotating the master cam shaft 70 and the cam shaft being ground in timed relation.

In testimony whereof I have signed my name to this specification.

HARRY HALES ASBRIDGE.
